UNITED STATES PATENT OFFICE.

ATHERTON D. CONVERSE, OF WINCHENDON, MASSACHUSETTS.

SPINNING-TOP.

1,325,000.

Specification of Letters Patent. Patented Dec. 16, 1919.

Application filed May 16, 1918; Serial No. 234,934. Renewed October 18, 1919. Serial No. 331,749.

To all whom it may concern:

Be it known that I, ATHERTON D. CONVERSE, a citizen of the United States, resident of Winchendon, Massachusetts, have 5 invented certain new and useful Improvements in Spinning-Tops, of which the following is a specification.

My invention relates to the general class 10 of tops which consist of a body or casing with a central spindle having a handle portion projecting above the body, said parts being assembled so that they may rotate in relation to each other, a spiral spring surrounding the spindle within the casing 15 and attached at one end to the body or casing and at its other end to the spindle, an example of such form of top being shown in Letters Patent of the United States granted to Gustave Haag, #453,473, June 2, 1891. 20 Such form of top is difficult to wind up as it has no means for temporarily holding the two parts, spindle and body, while the operator moves his hand or fingers for a new hold and it requires the use of both hands 25 in setting the top, after winding, in position to spin or in other words control of the top by both hands must be maintained until the top is set off. To avoid these objections a later form of this general type of top has 30 been provided with a ratchet like connection between the spindle and the casing or body which would hold these parts in the wound up or partially wound up condition until a new hold is secured for winding, or, if 35 wound, until by pressing down on the spindle the ratchet device would cease to function as a holding means and the spring would then set the body going in relation to the spindle, control of which by the hand 40 is momentarily maintained after the release of the ratchet.

Such a form of ratchet device is exemplified in Letters Patent of the United States, #1,253,195, to Scheell, January 8, 45 1918.

I have provided a top in which no ratchet means is present but yet the same effect can be secured by the fingers of one hand of the operator, that is maintaining the body or 50 the spindle in their partially wound up condition while the operator takes a new hold with his other hand for further winding or, in case the winding is completed, maintaining the parts in this condition until the 55 operator sets the top with one hand ready

to spin and until he releases the body for spinning.

In carrying out my invention I aim to provide a construction which is effective and susceptible of economical manufacture.

The invention consists in the features and combination and arrangement of parts hereinafter described and particularly pointed out in the claims.

In the accompanying drawings:— 65

Figure 1 is a side view of the top.

Fig. 2 is a sectional view.

Fig. 3 is a plan view.

In the drawing, 1 indicates the body or casing which may be made of various shapes 70 and of various kinds of material. In the particular form shown the material is thin sheet metal such as tin. A spindle 2 preferably of wood extends through a bearing at the top of the casing or body and it is 75 rotatively assembled with the lower portion of the casing. This may be accomplished in different ways but in the particular construction shown the spindle passes with a turning fit through a plate 3 suitably fixed 80 in the casing. In the particular form shown the sheet metal of the casing is formed to provide a shoulder at 4 for the plate to rest on and a tang may be provided at 5 to hold the plate in place. 85

The body or casing is provided with a stud 6 extending down therefrom which furnishes the point which bears on the supporting surface on which the top spins. This point may be held to the sheet metal 90 by a washer 7 forced onto the reduced shank 8 of the point.

The spindle extends above the casing or body and is provided with a suitable handle 9 by which the spindle may be turned 95 to wind up the spring 10. This spring is of spiral form. It surrounds the spindle and is attached thereto at its upper end while its lower end is attached to the casing or body and while this may be done in 100 various ways I prefer to run the end of the spring through openings in the plate 3.

Below the handle 9 I provide on the body or casing of the top a shoulder or finger grip 11. This is of such dimensions, form 105 and disposition in respect to the handle that when said handle portion of the spindle, whatever the shape or size thereof may be, is grasped by the thumb and forefinger these digits can overlap the same and press 110

thereon at the will of the operator or the operator may exert so little or no pressure of his thumb and forefinger on the side or circumferential surface of this boss that 5 the free movement of the body or casing in relation to the spindle is not retarded or interfered with.

In winding the top the operator holds the body or casing in one hand and with 10 the other hand he grasps the handle portion of the spindle and gives the same one turning action and at the end of this movement he grasps not only the handle but also the side surface of the boss or shoulder. 15 He is enabled to do this for, as stated above, a portion of the thumb and forefinger which grasps the handle also overlies the said surface and can press thereon at the will of the operator. While thus holding the casing or body and the spindle against relative turning movement the other hand can be shifted to take a new hold on the body for the next turning movement and in performing this the operator relieves the pressure of his fingers on the shoulder or boss and simply turns the spindle or the body or both. When the top is fully wound it may be held in this condition by the one hand so that the top may be set in the desired position for spinning, whereupon by releasing his hold first from the boss and then from the handle the top is set off and spins by reason of the uncoiling of the spring.

I prefer to form the handle portion of the spindle by providing an enlargement, as shown, at its upper end and this preferably has flattened sides at 13 so that not only can the spindle be more readily turned but there is a momentary dwell between the 40 time the fingers release the boss and the time they release the handle portion of the spindle and this slight difference in time is sufficient to allow the spring to set the body in rotation for the spinning of the top.

45 It will be seen from the above that the fingers of the hand which grasps the spindle acting on the adjacent surface of the body or casing which they overlie serve as the brake means to hold the body against rotation as long as the operator continues to exert pressure of his fingers on said surface. To express the matter in another way, the operator's fingers of the hand grasping the spindle serve in connection with the adjacent part of the body in place of the pawl and ratchet means heretofore employed as referred to above.

I claim:—

50 1. A spinning top comprising a body or casing, a spindle mounted therein for relative rotation of one in relation to the other, a spring connected to the spindle and body and adapted to be wound by turning one part relative to the other, said spindle hav-

ing a handle portion above the body and said body having a portion to be grasped by the fingers of the hand grasping the handle portion to hold the body and spindle against relative movement, substantially as described. 65 70

2. A spinning top comprising a body or casing, a spindle mounted therein for relative rotation of one in relation to the other, a spring connected to the spindle and body and adapted to be wound by turning one part 75 relative to the other, said spindle having a handle portion above the body and said body having a portion to be grasped by the fingers of the hand grasping the handle portion to hold the body and spindle against relative 80 movement, said body portion consisting of a boss or shoulder adjacent the handle portion of the spindle, substantially as described.

3. A spinning top having a body, a spindle journaled therein, a spring to spin the 85 top adapted to be wound by relatively turning the parts, said spindle having an enlarged handle portion above the body and said body having a portion adjacent the handle which the fingers of the hand grasping the handle can overlie and grasp for holding the parts against relative movement when wound or partially wound, substantially as described. 90

4. A spinning top having a body, a spindle journaled therein, a spring to spin the top adapted to be wound by relatively turning the parts, said spindle having an enlarged handle portion above the body, said body having a circular portion adjacent the 100 handle and of a diameter substantially equal to the width of the handle and which the fingers of the hand grasping the handle can overlie and grasp, substantially as described. 95

5. A spinning top having a body, a spindle journaled therein, a spring to spin the top adapted to be wound by relatively turning the parts, said spindle having an enlarged handle portion above the body, said body having a circular portion adjacent the 105 handle and of a diameter substantially equal to the width of the handle and which the fingers of the hand grasping the handle can overlie and grasp, said circular portion being in the form of a boss or shoulder of 110 reduced diameter in respect to the body of the top, substantially as described. 115

6. A spinning top having a body, a spindle journaled therein, a spring to spin the top adapted to be wound by relatively turning 120 the parts, said spindle having a handle portion above the body non-circular in form, said body having a circular portion adjacent said handle which the fingers of the hand grasping the handle can overlie and also 125 grasp, substantially as described.

In testimony whereof, I affix my signature,
ATHERTON D. CONVERSE,
